UNITED STATES PATENT OFFICE.

PETER EYLER, OF YORK, NEBRASKA.

COLLAPSIBLE EGG-CRATE.

1,314,862.

Specification of Letters Patent. Patented Sept. 2, 1919.

Application filed May 28, 1918. Serial No. 237,068.

To all whom it may concern:

Be it known that I, PETER EYLER, a citizen of the United States, residing at York, in the county of York and State of Nebraska, have invented certain new and useful Improvements in Collapsible Egg-Crates, of which the following is a specification.

This invention relates to knock-down crates, and more particularly to egg crates. One object of the invention is to provide a collapsible crate of extremely simple and practical construction, which may be quickly folded into compact form, suitable for shipping or storage.

Another object is to provide a folding crate which may be set up and collapsed in minimum time, with minimum labor, and which, when collapsed, will occupy minimum space.

Another object is to provide a crate of this character having locking bails for holding it in both set up and collapsed position.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a perspective view of a crate constructed in accordance with this invention set up ready for use with parts broken out.

Fig. 2 is a similar view of the crate collapsed ready for transportation with parts broken out,

Fig. 3 is a side elevation thereof,

Fig. 4 is a transverse vertical section taken on the line 4—4 of Fig. 3, and

Fig. 5 is an end elevation thereof.

In the embodiment illustrated, 1 represents the bottom of the crate which is constructed of sheet metal, preferably of galvanized iron and has upstanding side flanges 2 and end flanges 3, preferably made integral therewith, the free edges of these side and end members have hinge knuckles 2' and 3' formed by rolling the edges of said members inwardly, and which are designed to coöperate with similar knuckles 4' and 5' carried by the lower edges of side members

4 and end members 5, whereby said members are hingedly connected with the members 2 and 3.

The end members 5 are provided along 60 their side edges with laterally and inwardly extending right-angular flanges 6, which are designed to overlap the outer faces of the side members 4 when in set-up position to assist in holding them and to operate as reinforcements at the corners of the crate.

The end members 5 are provided on their outer faces with handles 7 for lifting the crate when filled.

Carried on the inner faces of the end 70 members 5 at their upper ends near the corners thereof are latches in the form of angular bracket-like members 8 pivotally connected at 9 to the end members 5, and having laterally opening slots in the free 75 end of its other arm. Studs 11 are carried by the inner faces of the side members 4 near the corners in position to be engaged by the slots 10 in the latches 8 when said latches are swung downwardly into operative position as shown in Fig. 1.

From the above description it will be obvious that to disengage these latches when the crate is to be collapsed, all that is necessary is to swing them upwardly on their 85 pivots 9 and then permit them to swing inwardly against the faces of their respective members. It is of course to be understood that one of these latches is placed at each corner of the crate.

A removable partition 12 is adapted to be disposed transversely within the crate with its ends engaged in seats 12' formed in the side walls of the members 4 as is shown clearly in Figs. 3 and 4. When the crate is 95 to be collapsed, this partition 12 is slipped out of its seats and placed within the crate.

Locking bails 13 composed of heavy wire or rods here shown substantially rectangular in form, are hingedly mounted in bearings 100 14 carried by the outer faces of the end members 5 as is shown clearly in Figs. 1, 3 and 5. These bails 13 are designed for locking the crate top 15 in position when the crate is either set up or collapsed, as is 105 shown in Figs. 1 and 2.

The top 15 has right-angularly disposed edge flanges 16 which are designed to fit over the upper edges of the side members 4 and end members 5 when the crate is set 110 up as shown in Figs. 1 and 3, and to fit over the members 2 and 3 when the crate is col-

lapsed as shown in Fig. 2. The side flanges of the top have cut-out portions or notches 17 therein to accommodate the ends of the bails when the crate is in collapsed position 5 as shown in Fig. 2.

Secured to the outer face of top 15 are a plurality of bail retaining members, three of which are here shown, two end members 18 and 19 and a centrally disposed member 10 20.

The end clips 18 and 19 open toward each other, and are designed to receive the free ends of the bails 13 when the crate is in collapsed position as is shown clearly in Fig. 15 2, and to yieldingly hold them in this position. The central clip 20 has a securing element 21 fastening it intermediately of its ends to the top 15 and its ends are bent to form bail engaging members 22 which open 20 in opposite directions to receive the free ends of the bail 13 when the crate is in set-up closed position as shown in Figs. 1 and 3.

It will thus be seen that with a crate constructed of sheet metal in the manner above 25 described, it may be readily set up and knocked down and held in either position by engagement of the locking bails with the clips as above described, the latches 8 operating to hold the side and end members 30 together when in set-up position.

This crate of course, may be made of any suitable or desired size, according to the number of eggs it is designed to carry.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the claimed invention.

Having thus fully described my invention, what I claim as new and desire to 45 secure by Letters Patent, is:—

1. A collapsible crate comprising a body portion having foldable side and end members, locking bails pivoted to the foldable end members, a removable top having flanges 50 to fit over said side and end members, and coöperating elements on said top for engagement by said bails whereby the members may be locked in either set up or collapsed condition.

55 2. A collapsible crate comprising a body portion having foldable side and end members, locking bails pivoted to the foldable end members, a removable top having flanges to fit over said side and end members, spring 60 clips carried by said top for engagement

with said bails for locking the side and end members in either set up or collapsed position.

3. A collapsible crate comprising a body portion having foldable side and end members, locking bails pivoted to the foldable end members, a removable top having flanges to fit over said side and end members, a centrally disposed spring clip on said top having bail receiving elements opening 70 in opposite directions to receive said bails and lock the crate when set up.

4. A collapsible crate comprising a body portion having foldable side and end members, locking bails pivoted to the foldable end members, a removable top having flanges to fit over said side and end members, a centrally disposed spring clip on said top having bail receiving elements opening 75 in opposite directions to receive said bails and lock the crate when set up, and clips spaced from said central clip on opposite sides thereof and opening toward each other to receive and lock said bails when the crate 80 is collapsed.

5. A collapsible crate comprising a bottom having upstanding side and end walls fixed thereto, side and end walls hinged to said fixed side and end walls and foldable inwardly, latch members pivotally mounted 85 on one of said foldable members, coöperating elements on said latch member and the adjacent foldable member for interlocking engagement whereby said members are held in upright position, bails pivotally mounted 90 on said foldable end members, a top flanged to fit over the upper ends of said foldable members when in operative position, and means on said top for engagement by said bails to lock the crate in set up position.

100 6. A collapsible crate comprising a bottom member, ends and sides hinged thereto to fold inwardly, detachable means for holding said members in upright operative position, a cover having flanges to shut down 105 over said members, the side flanges of said cover being notched, clips carried by its upper face, and bails pivoted on the other faces of said foldable end members and adapted to interlockingly engage said clips 110 whereby the crate may be locked in either set up or collapsed position, the bails lying in said flanged notches when the crate is collapsed.

In testimony whereof I affix my signature 115 in presence of two witnesses.

PETER EYLER.
